UNITED STATES PATENT OFFICE.

IDALYNE M. BEEMER, OF LOS ANGELES, CALIFORNIA.

SHOE-POLISHING CABINET.

1,147,779.

Specification of Letters Patent. Patented July 27, 1915.

Application filed November 16, 1914. Serial No. 372,330.

To all whom it may concern:

Be it known that I, IDALYNE M. BEEMER, a citizen of the United States, residing at Los Angeles, in the county of Los Angeles, State of California, have invented new and useful Improvements in Shoe-Polishing Cabinets, of which the following is a specification.

This invention relates to a shoe polishing cabinet.

It is the object of this invention to provide a shoe polishing cabinet, in which the patrons may pass to and from their positions on the stand without climbing up and down the latter in the presence of the employees and the public.

Another object is to provide a shoe polishing stand which is so constructed and arranged that the patrons and the employees will be separated in different compartments in which only the shoes of the patron will be exposed to the polishers.

Another object is to provide a shoe polishing stand having a partition for dividing the stand into two compartments, one for the patrons, and the other for the workmen, and in which the partition forms a table or desk for the use of the patrons during the shoe polishing operations.

Another object is to provide means in a shoe polishing cabinet of the above character for readily transmitting instructions to the workmen, together with means for signaling to the patrons when the work is complete.

A further object is to provide the stand with a slidable platform formed to extend on opposite sides of the footrests to enable the patrons to readily assume a position with the feet supported on the footrests, and in which the platform may be retracted by the workmen to give the necessary clearance at the sides of the footrests to perform the polishing operation.

The invention is illustrated in the accompanying drawing, in which:

Figure 1 is a view in vertical section of the cabinet partly in elevation illustrating the manner of using same. Fig. 2 is a horizontal section and plan view on the line 2—2 of Fig. 1.

In carrying out the present invention, the cabinet is constructed with four exterior walls 5, 6, 7 and 8 here shown as arranged in a rectangle with the space inclosed thereby divided into a series of compartments 9,

10 and 11 by means of transverse partitions 12 and 13; the structure being covered by a suitable roof 14 and provided with an entrance opening 16 leading to the compartment 9.

The compartment 9 constitutes a reception booth and is fitted with a seat 17 and table 18 and any other suitable conveniences. Leading from the reception booth 9 through an opening 19 in the partition 12 is a flight of steps 20 which terminate on an elevated platform 21 arranged in the compartment 10 and extending approximately half the width of the latter.

Extending across the compartment 10 between the walls or partitions 12 and 13 is a partition 22 which closes the space between the edge of the platform 21 and the wall 8 to form a pit or compartment 23 for the use of the workmen, which compartment 23 communicates with the compartment 11 through an opening 24. The compartment 11 is provided as a store room for the necessary supplies and is fitted with an entrance 25 by which access is gained to the compartments 11 and 23. The partition 22 is formed with an offset portion or shelf 26 which extends forward to a point above the edge of the platform 21 and spaced therefrom.

Mounted on the platform 21 adjacent the edge thereof is a series of revoluble chairs 27 in convenient relation to the shelf 26. Depending from the shelf 26 is a panel 28 forming part of the partition 22 which panel terminates on a plane slightly above the upper face of the platform 21 and spaced forward of the edge of the latter to form an opening 29 communicating between the compartments 10 and 23. Mounted on the forward wall of the platform 21 are brackets 30 arranged in pairs on the upper ends of which footrests 31 are supported; the footrests 31 being arranged substantially on a plane with the top of the platform 21 at a point directly beneath the panel 28.

Formed beneath the platform 21 is a space 32 in which a panel 33 is mounted to slide horizontally; the panel 33 being adapted to be extended forward of the edge of the platform 21 to constitute an extension of the latter and is formed with notches 34 on its outer edge to receive the footrests 31 so that the panel 33 will be positioned to extend on opposite sides of the footrests and to the outer ends of the latter.

In employing the present invention, the patrons enter the reception booth 9 and pass to the elevated platform 21 in the compartment 10 and take their seat on the revoluble chairs 27; the panels 33 being extended to enable the patrons to place their feet on the footrests 31. As a means for enabling the patrons to give instructions to the workmen in the pit or compartment 23 speaking tubes 10 35 are provided on the shelf 26. The workmen then retract the platform panel 33 and proceed to the shoe shining operations in the usual manner. When the work is complete a signal is transmitted to the patron 15 by turning on an electric light 36 mounted on the shelf 26.

By constructing a cabinet in the manner set forth desirable privacy and convenience is obtained; the patrons passing to and from 20 their position in the stand concealed from the view of passers-by and the workmen.

What I claim is:

1. A shoe polishing cabinet, comprising a compartment, an elevated platform therein, a second compartment, a partition separating 25 said second compartment from the first named compartment having a space therebeneath forming a communication between said compartments, chairs mounted on the 30 platform, and footrests arranged in the sec-

ond compartment adjacent the opening in the partition.

2. In a shoe polishing cabinet, a compartment, an elevated platform therein, a second compartment, a partition separating 35 said compartments having an opening adjacent the forward edge of the platform forming a communication between said compartments, footrests arranged in the second compartment and disposed adjacent said 40 opening, and a slideable panel on the platform adapted to extend on opposite sides of the footrests.

3. In a shoe polishing cabinet, a pair of compartments, one for the patrons and the 45 other for the workmen, an elevated platform in the patrons' compartment, footrests in the workmen's compartment arranged adjacent an opening communicating with the patrons' compartment, a shelf extending 50 over said opening, and a chair mounted on said platform adjacent the opening.

In witness that I claim the foregoing I have hereunto subscribed my name this 28th day of October, 1914.

IDALYNE M. BEEMER.
